(57) **CLAIM**

The ornamental design for a surveillance camera, as shown and described.

DESCRIPTION

FIG. 1 is a front perspective view illustrating my surveillance camera design;

FIG. 2 is a front elevational thereof;

FIG. 3 is a rear elevational thereof;

FIG. 4 is a right side elevational thereof;

FIG. 5 is a left side elevational thereof;

FIG. 6 is a top plan view thereof;

FIG. 7 is a bottom plan view thereof;

FIG. 8 is a front perspective view illustrating an alternative embodiment of my surveillance camera design;

FIG. 9 is a front elevational thereof;

FIG. 10 is a rear elevational thereof;

FIG. 11 is a right side elevational thereof;

FIG. 12 is a left side elevational thereof;

FIG. 13 is a top plan view thereof; and,

FIG. 14 is a bottom plan view thereof.

The broken lines shown herein are for illustrative purposes only and form no part of the claimed design.
